(57) **CLAIM**

The ornamental design for a blood glucose test meter, as shown and described.

DESCRIPTION

FIG. 1 is a front elevational view of the test meter.

FIG. 2 is a rear elevational view of the test meter.

FIG. 3 is a left elevational view of the test meter.

FIG. 4 is a right elevational view of the test meter.

FIG. 5 is a top plan view of the test meter.

FIG. 6 is a bottom plan view of the test meter.

FIG. 7 is a front perspective view 1 of the test meter.

FIG. 8 is a front perspective view 2 of the test meter; and,

FIG. 9 is a rear perspective view of the test meter.
